MUFFLER

Charles Demuth, Mineola, N. Y.

Application February 15, 1944, Serial No. 522,457

12 Claims. (Cl. 181—47)

This invention relates to mufflers for silencing or reducing noises caused by or carried by a gas (such as exhaust gas from an internal combustion engine, air, vapor, steam or the like compressible fluid) in its movement through or from a conduit.

A familiar application of this class of device is typified by the muffler employed in connection with the exhaust of an internal combustion engine. As illustrative of other applications, I have employed the present invention in air conditioning and ventilating conduits or ducts with excellent success.

An object of the invention is to provide a device which will act as an efficient silencer, while at the same time substantially eliminating back pressure.

Another object is to provide a muffler which greatly reduces or eliminates back pressure while at the same time preventing or greatly retarding a reversal of the flow of gas (such as a backfire).

The invention consists of the novel feature, arrangement and combination of parts embodied by way of example in the structure hereinafter described as illustrating the present preferred form of the invention, and the invention will be more particularly pointed out in the appended claims.

Further objects and advantages of the invention will more fully appear from the following description taken in connection with the accompanying drawings which show, by way of example, present preferred embodiments of the invention.

Referring to the drawings—

Fig. 1 is a longitudinal sectional view, taken in a plane passing substantially through the axis of a preferred embodiment of the invention, and showing the interior construction thereof;

Fig. 2 is a transverse sectional view taken along the line 2—2 of Fig. 1 and showing certain details at the inlet end;

Fig. 3 is a transverse sectional view taken along the line 3—3 of Fig. 1 and showing certain details at a zone intermediate the inlet and outlet ends;

Fig. 4 is a view similar to Fig. 1 but showing a modified embodiment of the invention;

Fig. 5 is a cross-sectional view taken at line 5—5 of Fig. 4; and

Fig. 6 is a cross-sectional view showing somewhat more clearly certain details common to the embodiments of Figs. 1 and 4.

Referring more particularly to Fig. 1, 1 designates in general the casing or main body struc-

ture of the muffler which comprises two sections 2 and 3 of generally frusto-conical shape secured together at their bases such as by flange rings 4 and 5 integrally secured thereto as by welding, and bolted together around their peripheries by bolts such as 6. The outer small ends of the sections 2—3 are provided with cylindrical sleeve portions 7 and 8, serving respectively as the inlet and outlet ends of the muffler and providing means for attachment to suitable conduits. The casing 1 is substantially circular in cross-section and is provided on its inner face with a plurality of substantially frusto-conical annular rings such as 9—24 inclusive, which are suitably secured at their respective outer edges to the interior of the casing 1, as by welding. It will be noted that the annular rings 9—24 are spaced axially in generally nested arrangement so that the small end of one ring extends into the large end of the succeeding ring or is directed into the large end of the succeeding ring. The inner edges of the rings 9—24 are spaced inwardly from the side wall of casing 1 and define the same general configuration as the casing 1. It will also be noted that the baffle rings 9—24 inclusive taper inwardly in a direction from the inlet throat 7 toward the outlet throat 8, i. e., in the direction of flow through the muffler.

A centrally disposed series of substantially frusto-conical baffle members 25—37 inclusive is supported substantially along the axis of the casing 1, i. e., the axis of the sleeves 7—8; in the present embodiment such support being had from the central baffle member 30 which is provided with a plurality of spider arms 38, 39 (Fig. 3), 40 and 41, which carry integrally supported at their outer ends an annular flange 42 which is secured between the flanges 4 and 5 so as to rigidly support the baffle member 30 in substantially the axial position indicated in Fig. 1. An axially extending bolt or threaded rod 43 (Fig. 1) extends through a hole provided in the baffle cone 30 and through corresponding holes in the remaining baffles 25—29 and 35—37 inclusive of the central series; these baffles being spaced one from the other by means of spacing sleeve such as 44, and the entire assembly being secured to the cone 30, such as by a nut 45. In the present embodiment I have found it convenient to support the baffles 31—34 inclusive directly from the baffle 30, as by welding the small ends of these frusto-conical members to the inside of the member 30, as clearly shown in Fig. 1.

The baffle members 25—37 inclusive extend outwardly from the axis of the muffler and incline

outwardly toward their large diameters in a direction from the inlet opening towards the outlet opening; with the outer circumferential edges of said central baffles spaced inwardly from the inner edges of the outer series of baffles and defining the same general shape as that followed by the inner edges of the outer baffles. The assembly of central baffles is disposed within the path of the flow of gas entering the inlet opening, and serves to deflect the gases outwardly and through the annular space defined between the respective inner edges of the outer series of baffles and the outer edges of the inner series of baffles. An examination of Fig. 1 will show that with the arrangement as above described the outer baffles such as 11-23 and the respective inner baffles 25-37 provides in effect a plurality of annular nozzles providing annular orifices through which gases successively pass from the inlet to the outlet openings of the muffler; this arrangement being somewhat more clearly shown in Fig. 6. It is not essential, however, that every baffle of one series have a corresponding baffle of the other series. It is noted that the annular area of the orifices of these successive nozzles is greater than the intake orifice, and this is controlled by the internal diameter of the outer series and outer diameter of the inner series of said baffles.

In the present embodiment, the annular outer baffles 9, 10 and 24 do not have any corresponding inner central baffles but cooperate with the remaining baffles of the outer series to create a so-called vacuum or reduced pressure within the successive spaces defined between the outer baffles and the adjacent interior of the casing 1. Similarly the spaces between the inner series of baffles 25-37 inclusive and their supporting axle provide the so-called vacuum or reduced pressure due to the movement of gases in the manner above described. Additionally, the arrangement of baffles, while permitting free passage of gas from the inlet to the outlet ends of the muffler, substantially prevents a flow in the reverse direction; and in view of the relatively large annular vacuum spaces provided between the baffles, any backfire will be practically prevented from causing any appreciable flow in a reverse direction out through the inlet of the muffler.

I have found that the preferable proportions for the muffler are as follows: The outlet is generally the same size as the inlet and should not be appreciably smaller, but may be larger. The maximum internal diameter (say, at the intermediate zone designated by the ring flange 42) should be twice as great as the diameter of the inlet opening, i. e., at least twice the area; and the axial length of the muffler from the inner end of the inlet sleeve 1 to the inner end of the outlet sleeve 8 should be at least twice as great as the maximum diameter above referred to. I have obtained satisfactory results in an embodiment of the invention where the inlet and outlet openings were each three inches in diameter; the axial length was twelve inches; and the maximum diameter was approximately six inches. It will be understood by those skilled in the art, after understanding my invention, that these dimensions may be varied, within the teaching of the invention; and the taper of the baffles and number of baffles employed may be varied. Such variation will be found expedient in accordance with the character of use, as will be understood by those skilled in the art.

Modification (Fig. 4)

In Fig. 4 I have shown a modification which in major particulars as to baffle arrangement and shape is similar to the embodiment previously described with reference to Fig. 1; and therefore the description of features common to both embodiments will not be repeated, and similar parts of Fig. 4 will be designated by corresponding reference numerals with an added prime suffix.

The muffler casing 1' is shown in this embodiment as comprising the sections 2'-3' joined together at the intermediate maximum diameter by a seam 46 which may be formed in any suitable manner such as by welding together flanged peripheral edges of the abutting sections. Instead of supporting the central baffle set from a single spider disposed at the median zone of the muffler (as in the previously described embodiment), the central baffle set is supported from suitable spider rings, such as 47 and 48, rigidly secured within the respective inlet and outlet throats 7'-8', as by spot-welding. A tie-rod or bolt 43' passes through the hubs of the spider rings 47-48 and is rigidly supported thereby substantially along the axis of the muffler. The baffle members 25'-37' are threaded on to the rod 43' and are rigidly held in spaced relation by suitable spacing sleeves such as 44'; and oppositely disposed spacing sleeves 49 and 50 serve to axially space the respectively opposite ends of the series of central baffles from the respectively adjacent spider rings 47 and 48. It will thus be seen that the core unit assembly of baffles of the central series are rigidly supported axially of the muffler in the position corresponding to that previously described; but in this instance the support is had from the opposite ends of the muffler instead of from a central zone as described in the previous embodiment.

It is noted that the embodiment of Fig. 1 permits ready disassembly and reassembly; and this is especially useful when the muffler is used under such circumstances as require cleaning.

Operation

The gas flowing in through the inlet, such as 7 or 7', passes through the annular rings, such as 9-10 or 9'-10', and is gradually and progressively deflected or expanded outwardly by the inner baffles 25-30 or 25'-30' toward and against the outer baffles 11-17 or 11'-17' to adjacent the median zone, and then is gradually and progressively deflected inwardly by the outer series 17-22 or 17'-22' toward or against the inner series of baffles 32-37 or 32'-37'. The gas is thus caused to flow in the annular passage defined between the outer edges of the inner baffles and the inner edges of the outer baffles, such as 9-24 or 9'-24', and thence outwardly through the annular baffle ring, such as 24 or 24', and outwardly through the outlet opening, such as 8 or 8'. During the flow of the gas through the muffler, the baffle arrangement produces a reduced pressure in the spaces between the baffles, as previously described; thus providing adjacent the interior surface of the muffler shell 1 or 1' a layer of reduced pressure or partial vacuum serving as sound absorber or dissipator. Correspondingly, a central core of reduced pressure or partial vacuum is created by the baffles of the central series of baffles. Accordingly, the noises caused or carried by the moving flow of gas are insulated and absorbed or dissipated during the passage through the muffler. In practical operation the invention has been found to be most efficient in elimination of noises, pre-

venting a reversal of flow of gases, and eliminating the creation of back pressure, which is especially desirable in internal combustion engines.

Having thus described my invention with particularity with reference to presently preferred forms of the same, it will be obvious to those skilled in the art after understanding the invention, that various other changes and modifications may be made therein without departing from the scope of the invention, and it is my intention to cover in the appended claims such changes as come within the scope of the invention.

What I claim is:

1. A muffler comprising a casing provided with substantially axially disposed inlet and outlet openings at respectively opposite ends, a first series of axially spaced baffles surrounding the axis of and extending inwardly of said casing in the general direction of said outlet opening, a second series of axially spaced baffles extending outwardly from the axis of said casing and inclined toward said outlet opening, the baffles of said second series increasing in outward extent from adjacent the respective inlet and outlet ends to a zone intermediate said ends and the inwardly extending edges of the baffles of said first series being spaced outwardly therefrom to provide intermediate said two series of baffles a free annular passage flaring outwardly from the respective inlet and outlet ends toward said intermediate zone in general funnel shape.

2. A muffler comprising a substantially circular casing provided with substantially axially disposed inlet and outlet openings at respectively opposite ends, a first series of axially spaced baffles surrounding the axis of and extending inwardly of said casing inclined in the general direction of said outlet opening and having their outer peripheries rigidly secured to the interior of said casing, a second series of axially spaced baffles extending outwardly from the axis of said casing inclined toward said outlet opening and supported on an axially extending rod supported from said casing, the baffles of said second series progressively increasing in outward extent from adjacent the respective inlet and outlet ends to a zone intermediate said ends and the inwardly extending edges of the baffles of said first series being spaced outwardly therefrom to provide intermediate said two series of baffles a free annular passage between said inlet and outlet openings.

3. A muffler comprising a substantially circular casing provided with substantially axially disposed inlet and outlet openings at respectively opposite ends, a first series of axially spaced frusto-conical ring baffles whose large diameters are secured to the inner wall of said casing and whose small diameters are directed toward said outlet opening, whereby the baffles provide successive throats decreasing in area toward said outlet, a second series of axially spaced substantially circular baffles extending outwardly from the axis of said casing and inclined toward said outlet opening, the baffles of said second series progressively increasing in outward extent from adjacent the respective inlet and outlet ends to a zone intermediate said ends and the inwardly extending edges of the baffles of said first series being spaced outwardly therefrom to provide intermediate said two series of baffles a free annular passage between said inlet and outlet openings.

4. A muffler comprising a substantially circular elongated casing provided at respectively opposite ends with inlet and outlet openings and pro-

gressively increasing in diameter from adjacent said respective openings to a maximum diameter at a zone intermediate said ends, an outer series of axially spaced annular baffles integrally secured within said casing and directed inwardly thereof and toward said outlet opening with their inner peripheral edges spaced inwardly from and conforming to the general contour of said casing, and an inner series of axially spaced baffles respectively extending in a direction outwardly from said axis and inclined toward said outlet opening, the outer peripheral edges of said inner baffles being spaced inwardly from the inner edges of said outer baffles to define a free annular passage conforming to the general contour of said casing and interconnecting said inlet and outlet passages.

5. A muffler comprising a substantially circular elongated casing provided at respectively opposite ends with inlet and outlet openings and progressively increasing in diameter from adjacent said respective openings to a maximum diameter at a zone intermediate said ends, said maximum diameter being at least twice the diameter of said inlet opening and said outlet opening being of a diameter at least substantially as large as the diameter of said inlet opening, an outer series of axially spaced annular baffles integrally secured within said casing and directed inwardly thereof and toward said outlet opening with their inner peripheral edges spaced inwardly from and conforming to the general contour of said casing, and an inner series of axially spaced baffles respectively extending in a direction outwardly from said axis and inclined toward said outlet opening, the outer peripheral edges of said inner baffles being spaced inwardly from the inner edges of said outer baffles to define a free annular passage conforming to the general contour of said casing and interconnecting said inlet and outlet passages.

6. A muffler comprising a substantially circular elongated casing provided at respectively opposite ends with inlet and outlet openings and progressively increasing in diameter from adjacent said respective openings to a maximum diameter at a zone intermediate said ends, said maximum diameter being at least twice the diameter of said inlet opening and said outlet opening being of a diameter at least substantially as large as the diameter of said inlet opening, the axial length of said casing being at least twice the maximum diameter, an outer series of axially spaced annular baffles integrally secured within said casing and directed inwardly thereof and toward said outlet opening with their inner peripheral edges spaced inwardly from and conforming to the general contour of said casing, and an inner series of axially spaced baffles respectively extending in a direction outwardly from said axis and inclined toward said outlet opening, the outer peripheral edges of said inner baffles being spaced inwardly from the inner edges of said outer baffles to define a free annular passage conforming to the general contour of said casing and interconnecting said inlet and outlet passages.

7. A muffler comprising a substantially circular elongated casing provided at respectively opposite ends with inlet and outlet openings and progressively increasing in diameter from adjacent said respective openings to a maximum diameter at a zone intermediate said ends, an outer series of axially spaced annular baffles integrally secured within said casing and directed inwardly thereof and toward said outlet opening with their

inner peripheral edges spaced inwardly from and conforming to the general contour of said casing, and an inner series of axially spaced baffles respectively extending in a direction outwardly from said axis and inclined toward said outlet opening, the outer peripheral edges of said inner baffles being spaced inwardly from the inner edges of said outer baffles to define a free annular passage conforming to the general contour of said casing and interconnecting said inlet and outlet passages, said inner series of baffles extending coaxially of and for the major part of the axial distance between said inlet and outlet openings, and the baffles of said inner series which are contiguous said intermediate zone of said casing being of substantially greater diameter than said inlet opening.

8. A muffler comprising a casing member having an inlet opening and an outlet opening, and a plurality of substantially concentric annular baffle nozzles spaced apart axially of said casing and having respective inner and outer annular side walls converging toward their outlet ends to provide a plurality of restricted annular orifices whose respective internal and external diameters increase in size from said casing inlet end to an intermediate zone of said casing and decrease therefrom toward said casing outlet end, said nozzles defining a free passage from said inlet opening to said outlet opening.

9. A muffler comprising a casing member having an inlet opening and an outlet opening, and a plurality of substantially concentric annular baffle nozzles spaced apart axially of said casing and having respective inner and outer annular side wall members converging toward their outlet ends to provide a plurality of restricted annular orifices whose respective internal and external diameters increase in size from said casing inlet end to an intermediate zone of said casing and decrease therefrom toward said casing outlet end, said nozzles defining a free annular passage between said inlet and outlet openings, said nozzle outer side wall members being secured at their outer peripheries to the interior of said casing member, and said nozzle inner side wall members being supported as a unit in substantial alignment with said inlet and outlet openings for deflecting the flow from said inlet opening into said annular passage.

10. A muffler comprising a casing member having an inlet opening and an outlet opening, and a plurality of annular baffle nozzles spaced apart in nested relation axially of said casing so as to successively discharge each into another in the direction of flow from said inlet opening to said outlet opening, and having respective inner and outer annular side walls converging toward their outlet ends to provide a plurality of restricted annular orifices whose respective internal and external diameters progressively in-

crease in size from said casing inlet end to an intermediate axial zone of said casing and progressively decrease therefrom toward said casing outlet end, said nozzles defining a continuous passage between said inlet and outlet openings.

11. A muffler comprising a casing unit provided with axially disposed inlet and outlet openings and a core unit, said casing unit comprising a hollow substantially circular elongated body provided with a plurality of circumferentially extending axially spaced baffle members extending interiorly of said body and inclined toward said outlet opening, the inner edges of said baffles defining a double oppositely tapering frusto-conical shape whose opposite smaller diameters are contiguous respective of said inlet and outlet openings, said core unit comprising an axially disposed member rigidly supported by said casing unit and carrying fixed thereto a plurality of axially spaced baffle members of generally frusto-conical shape and whose side walls taper outwardly and toward said outlet opening, the inner edges of said core baffles defining a double frusto-conical shape whose side walls are spaced inwardly from the inner edges of said casing baffles to provide a free passage from said inlet opening to said outlet opening.

12. A muffler comprising a casing unit provided with axially disposed inlet and outlet openings and a core unit, said casing unit comprising a hollow substantially circular elongated body provided with a plurality of circumferentially extending axially spaced baffle members of generally frusto-conical ring shape and whose bases are attached to the inner surface of said body and whose small ends are directed toward said outlet opening, the inner edges of said baffles defining a double oppositely tapering frusto-conical shape whose opposite smaller diameters are contiguous respective of said inlet and outlet openings, the maximum diameter of said body being at least twice the diameter of said inlet opening, said core unit comprising an axially disposed member rigidly supported by said casing unit and carrying fixed thereto a plurality of axially spaced baffle members of generally frusto-conical shape and whose side walls taper outwardly and toward said outlet opening, the maximum diameter of said core being greater than the diameter of said inlet opening, and the oppositely disposed end baffles of said core being substantially smaller than the respective adjacent inlet and outlet openings, the inner edges of said core baffles defining a double frusto-conical shape whose side walls are spaced inwardly from the inner edges of said casing baffles to provide a free passage from said inlet opening to said outlet opening.

CHARLES DEMUTH.
